CHILD'S NURSING STAND

Rodolfo Luzardo, Chacao, Venezuela

Application September 11, 1945, Serial No. 615,589

9 Claims. (Cl. 128—1)

1

This invention relates to a child's nursing stand.

The primary object of the invention resides in a stand for supporting an infant child in a reclining position for feeding direct from a mother's breast, thus eliminating the necessity of the mother holding the child during such feeding period.

Another feature of the invention is to provide a child's nursing stand adjacent which a nursing mother may assume a comfortable sitting position in a chair with both hands free, while the infant child is supported by the stand in a manner to directly nurse upon either breast without necessitating the mother changing her position relative to the stand.

A further feature of the invention is the provision of a child's nursing stand which is adjustable as to height to suit the height of a mother in a sitting position, and which is further adjustable to support a nursing infant child in various inclined positions as well as in a horizontal position to meet the comfort of the nursing child.

Other features of the invention are to provide a strong and durable adjustable nursing stand for infants; to provide such a stand which is portable so as to be moved into an out-of-the-way place when not in use; and in which the breast holder may be easily separated from the stand and thoroughly cleansed after each use to maintain the same in a sanitary condition.

Other novel features of the invention will become apparent as the following specification is read in conjunction with the accompanying drawing in which

Figure 1 is a side elevational view of a child's nursing stand constructed in accordance with my invention.

Figure 2 is an end elevational view looking toward the left of Figure 1.

Figure 3 is an enlarged horizontal sectional view on the line 3-3 of Figure 2.

Figure 4 is a detail sectional elevational view of a nursing bottle holder attachment.

Referring to the drawing by reference characters, the numeral 10 designates a child's nursing stand constructed in accordance with my invention, and which includes a vertically adjustable pedestal 11.

The pedestal 11 comprises a base 12 and an upstanding post 13. The base 12 is relatively heavy to counterbalance the weight of an infant child and its support which is carried by the upper end of the pedestal 11 in a manner to be pres-

ently explained. The base 12 is provided with ball casters 14 to enable the stand to be easily slid over a floor to a position of use and to an out-of-the-way place when not in use.

5 The post 13 comprises a lower tubular post section 15 and an upper post section 16 which has its lower portion slidably fitting into the upper end of the post section 15. The lower portion of the upper post section 16 is provided with
10 screw threads 17 to which an adjusting nut 18 is threaded, said nut seating upon the upper end of the post section 15. By turning of the nut 18, the upper post section 16 may be raised or lowered with respect to the lower post section
15, thereby varying the height of the pedestal for reasons to be hereafter appreciated.

20 Formed integral with the upper end of the post section 16 is a flat head 19 having a central bearing aperture 20 whose axis is at a right angle or transverse to that of the upper post section 16. The apertured head 19 constitutes a bearing support for an outwardly extending arm 21.

The arm 21 comprises an inner arm section 22 and an outer arm section 23. The inner end of the arm section 22 has a bearing portion 24 which is journalled in the aperture 20. Adjacent the bearing portion 24, the arm section 22 is provided with an annular flange 25 which has sliding contact with the adjacent flat side 30 face of the head 19. The head 19, surrounding the flange 25, is provided with annular series of teeth 26 which is engaged by the annular series of teeth 27 provided on a clutch member 28. The teeth 27 of the clutch member are normally held engaged with the teeth 26 of the head by an expansion spring 29 which is interposed between the sleeve of the clutch member and a shoulder 30 defined by the inner end of an enlarged bifurcated tooth segment 31. The inner end of the outer arm section 23 fits into the bifurcated segment and is connected thereto by a pivot pin 32. Extending from that end of the bearing portion 24 opposite to that at which the flange 25 is formed, is a threaded shank 33 carrying a washer 34 and a nut 35. When the nut 35 is tightened against the washer, the arm 23 is free to rotate about the axis of the inner arm section 22, such movement being arrested by the clutch member 28 which is slidably keyed to the inner arm section and in interlocking engagement with the head 19.

In order to lock the outer arm section 23 in an angular position of adjustment relative to the inner arm section 22, I provide a sliding clutch collar 36 upon the arm section 23. The clutch

collar 36 is provided with teeth 37 which engage the teeth of the tooth segment 31. The clutch member 36 is normally held engaged with the segment by an expansion spring 39 which is interposed between the member 36 and the collar 38 of a hand grip member 40 fixed to the arm section 23.

Means is provided for simultaneously moving the clutch members 28 and 36 to a releasing position against the tension of the springs 29 and 39, and which includes an actuating lever 41 pivoted to the hand grip member 40. The manipulating portion of the lever 41 is so located relative to the hand grip member that when the hand of an operator is grasping the member 40, the thumb of said hand may reach the lever to actuate the same. The forks 42 of the lever 41 have the outer ends of flexible links 43 respectively connected thereto, said links also being connected to pins 44 and 45 extending outwardly from the clutch members 36 and 28 respectively. The hand grip member 40 enables the outer arm section 23 to be supported by an operator when the lever 41 is actuated to release the clutch members 36 and 28 when it is desired to effect an axial adjustment of the arm 21 and/or an angular adjustment of the outer arm section 23 relative to the inner arm section 22.

The outer end of the arm 21 supports a basket-like platform 46 which includes a head end 47 and a foot end 48. A stub shaft 49 depends from the underside of the platform 46 adjacent the mid-portion thereof and has a toothed wheel 50 fixed thereto. The lower end of the stub shaft 49 is journaled in a bearing 51 provided at the outer end of the arm section 23 whereby the platform is free to be rotated about the axis of the stub shaft 49 to enable the reversing of the head and foot ends of the platform for reasons to be hereafter explained.

Means is provided for releasably locking the platform against rotation and which embodies the toothed wheel 50. A tooth member 52 slidably mounted in a housing 53 at the underside of the platform 46 normally engages the toothed wheel 50 by the action of a spring 54. An actuating arm 55 has its inner end connected to the tooth member 52 while its outer end terminates in a finger loop 56 adjacent the foot end 48 of the platform. By inserting one's finger in the loop 56 and pulling outward, the tooth member 52 may be disengaged from the toothed wheel 50, whereupon the platform 46 is free to be rotated.

The underside of the platform 46 at the head end 47 is provided with a flat eye 57 having a clamping screw 58 threaded therein. The eye 57 is adapted to interchangeably support a breast holder 59 shown in Figures 1 and 2 or a nursing bottle holder 60 shown in Figure 4.

The breast holder 59 comprises a cup-shaped member 61 having a central nipple aperture 62. Radial openings 63 are provided in the member 61 to provide ventilation when the breast of a nursing mother is positioned in the cup-shaped member with the nipple thereof extending through the central aperture 62. The member 61 is supported by the short upstanding arm of an L-shaped bracket 64, the long arm thereof extending through the eye 57 and held against sliding by the clamping screw 58.

The nursing bottle holder 60 is substituted for the breast holder member 59 when the infant child is to be fed from a bottle instead of direct from the breast of a nursing mother. The holder 60 comprises a bracket base 65, a bendable arm 66

rising from the outer end of the bracket, and a bottle holder member 67 at the upper end of the arm 66 in which a nursing bottle 68 is removably fitted.

In use of the stand 10, assume that a nursing mother is desirous of nursing her child direct from her breast. The pedestal 11 is adjusted to the proper height for the mother's breast to comfortably fit into the cup-shaped member 61 while the mother is in a seated position in a chair with the stand 10 drawn up close. The platform 46 is adjusted on the axes of the stub shaft 24, pivot pin 32, and stub shaft 49, to the desired position to suit the comfort of the child. After the desired adjustments have been made, the child to be nursed is placed upon the platform 46 in a lying position with its head at the head end 47 and its mouth at the aperture 62 of the breast holder member 61. Assume that the platform is in the position shown in Figure 1 wherein the head end thereof is at the right. The nursing mother places her right breast into the cup-shaped member 61 with the nipple thereof extending through the aperture 62 whereupon it may be reached by the lying upon the platform. After the child has nursed on the right breast and it is desired that it nurse upon the left breast, the mother grasps the loop 56 and pulls outwardly thereon to disengage the tooth member 52 from engagement with the tooth wheel 50, and while still grasping the loop 56, she imparts a 180° turn to the platform 46 with the child still reclining thereon. Upon releasing the loop 56, the tooth 52 again engages the tooth wheel 50 and the platform is again locked against turning. The head end 47 is now at the left and by removing the cup-shaped member 61 from what is now the rear side and replacing it at the left side in the eye 57 the device is now ready to receive the left breast in the member 61 for nursing thereon by the child.

During and after nursing of a child it is often necessary to raise the child to an upright position to relieve the same of stomach gases. This may be accomplished without removing the child from the platform by turning the arm 21 on the axis of the inner arm section 22 so that the foot end 48 of the platform will tilt downwardly.

If desired, suitable harness may be provided to securely hold the child upon the platform, for by the various adjusting means which control the positions of the outer arm section 23, the platform may be tilted sidewise as well as lengthwise in either direction.

For the comfort of the nursing mother while seated at the nursing stand 10, I provide foot rests 69 on the lower post section 15 just above the base 12.

While I have shown and described what I consider to be the preferred embodiment of my invention, I wish it to be understood that such changes in construction, design and materials as come within the scope of the appended claims may be resorted to if desired without departing from the spirit of my invention as set forth in the appended claims.

Having thus described my invention, what I claim as new and desire to secure by Letters Patent is:

1. A child's nursing stand comprising a pedestal, an arm attached to the upper end of the pedestal and extending outwardly therefrom, a platform rotatably supported at the outer end of said arm on an axis transverse to said arm, said platform having a head end, a breast holder, means for supporting said breast holder at either

side of the head end of said platform, and releasable latch means for securing the platform against rotation when the same is turned to an adjusted position.

2. A child's nursing stand comprising a pedestal, means for adjusting the height of said pedestal, an arm rotatably mounted on a horizontal axis at the upper end of said pedestal, releasable means for securing said arm against rotation, a platform rotatably supported at the outer end of said arm on an axis transverse to that of said arm, said platform having a head end, a breast holder, means for supporting said breast holder at either side of the head end of said platform, and releasable latch means for securing the platform against rotation about its rotating axis when the same is turned to a desired adjusted position.

3. A child's nursing stand as set forth in claim 2 in which the arm comprises an inner arm section, an outer arm section pivotally connected to the inner arm section, and releasable means for securing the outer arm section in various angular positions of adjustment relative to the inner arm section.

4. A child's nursing stand as set forth in claim 2 in which the arm comprises an inner arm section, an outer arm section pivotally connected to the inner arm section, releasable means for securing the outer arm section in various angular positions of adjustment relative to the inner arm section, and a single hand-operated actuating means for simultaneously releasing the releasable means for securing the arm against rotation and also the releasable means for securing the outer arm section in various positions of adjustment.

5. A child's nursing stand as set forth in claim 2 in which the releasable latch means includes a tooth wheel, and a finger operated spring catch member engaging said tooth wheel.

6. A child's nursing stand comprising a pedestal having a relatively heavy base, a rigid arm attached to the top of said pedestal and extending outwardly therefrom, a basket like platform rotatably mounted on a vertical axis at the outer end of said arm, said platform having a head end and a foot end whereby upon one half revolution

of the platform will effect a reversal of the position of the head and foot ends, releasable means for locking the platform against rotation, a nursing holder member, and means for interchangeably mounting the nursing holder member upon opposite sides of the head end of said platform.

7. A child's nursing stand as set forth in claim 2 in which the arm comprises an inner arm section, an outer arm section pivotally connected to the inner arm section, releasable means for securing the outer arm section in various angular positions of adjustment relative to the inner arm section, and a single hand-operated actuating means for simultaneously releasing the releasable means for securing the arm against rotation and also the releasable means for securing the outer arm section in various positions of adjustment, and a hand grip attached to the outer arm section and associated with the hand actuated means for manually supporting the arm when the arm sections are in released position.

8. A child's nursing stand comprising a pedestal, a rigid arm extending outwardly from the pedestal, a platform supported by said arm, and means for connecting said arm to the pedestal for permitting tilting of the platform in a plane transverse to said arm, said means comprising clutch parts on said arm and pedestal.

9. A child's nursing stand comprising a pedestal, a rigid arm attached to the pedestal and extending outwardly therefrom, a platform supported by said arm, the latter comprising two sections, substantially horizontal means for pivotally connecting the sections so that the platform can be raised and lowered about said means as an axis, and means for securing the sections of said arm in adjusted position.
